UNITED STATES PATENT OFFICE

166,154

TELEVISION TIMETABLE

William L. Garrett, Jr., Los Angeles, Calif.

Application April 11, 1950, Serial No. 9,125

Term of patent 3½ years

(Cl. D56—1)

To all whom it may concern:

Be it known that I, William L. Garrett, Jr., a citizen of the United States, residing at Los Angeles, in the county of Los Angeles and State of California, have invented a new, original, and ornamental Design for a Television Timetable, of which the following is a specification, reference being had to the accompanying drawing, forming part thereof.

Figure 1 is a view in top plan of a television timetable embodying my new design; and

Figure 2 is a view in end elevation.

The numerals appearing in Figure 1 are merely representative of what might appear thereon from time to time.

I claim:

The ornamental design for a television timetable, substantially as shown and described.

WILLIAM L. GARRETT, JR.
